UNITED STATES PATENT OFFICE.

ORVILLE D. BENDURE, OF MOUND CITY, KANSAS.

RIDING ATTACHMENT FOR CULTIVATORS.

1,303,533.

Specification of Letters Patent.

Patented May 13, 1919.

Application filed August 17, 1917. Serial No. 186,741.

To all whom it may concern:

Be it known that I, ORVILLE D. BENDURE, a citizen of the United States, residing at Mound City, in the county of Linn, State of Kansas, have invented certain new and useful Improvements in Riding Attachments for Cultivators; and I do hereby declare the following to be a full, clear, and exact description of the invention, such as will enable others skilled in the art to which it appertains to make and use the same.

This invention relates to improvements in cultivator attachments and particularly to riding attachments for cultivators.

One object of the present invention is to provide a novel and simple device of this character which can be quickly and easily applied to the ordinary cultivator frame.

Another object is to provide a device of this character whereby the driver will be more comfortably placed on the machine and can more readily manipulate the shovels of the cultivator.

Other objects and advantages will be apparent from the following description when taken in connection with the accompanying drawing.

In the drawing:

Figure 1 is a side elevation of a portion of a cultivator showing my improved riding attachment in connection therewith.

Fig. 2 is a top plan view of the same.

Fig. 3 is a transverse sectional view taken on the line 3—3 of Fig. 2.

Fig. 4 is a transverse sectional view taken on the line 4—4 of Fig. 2.

Referring particularly to the accompanying drawing 10 represents the arch of the cultivator which includes the oppositely extending axle portions 11 for the ground engaging wheels 12. Secured to the upper central portion of the arch is the usual tongue 13, one portion of which extends a suitable distance to the rear of the arch and carries the usual hooks 14 for holding the beams 15 in elevated position. Disposed on opposite sides of the beam or tongue 13, and extending forwardly and rearwardly of the arch, are the bars 16, the forward end of each of which is turned laterally outwardly as shown at 17. Each of these outturned portions is formed with a longitudinal series of openings 18, the purpose of which will presently appear. The intermediate portion of each bar 16 is formed with a series of notches on the lower edge for the reception

of the portions of the arch at opposite sides of the tongue. An angular U-shaped plate 19 connected to the forward portions of the bars, holds said bars in proper spaced relation. By means of these notches 16', the bars 16 can be moved longitudinally with respect to the tongue and thus regulate the distance the seat 20 is desired to the rear of the cultivator. A second U-shaped plate 21 connects the rear portions of the bars 16 together. The seat 20 is secured on the rear ends of the bars 16 by means of the usual clip 22 and bolt 23.

The beams of the cultivator are disposed in pairs, as clearly shown in Fig. 2, and connecting these beams in pairs are the transverse braces 24. Secured respectively to each of the braces, and to one of each pair of beams, is a clip or clamp 25, a bar 27 being secured to and extending between each pair of the clips and having suitably secured thereon a stirrup or foot plate 28.

Connected to each of the portions 17 is the forward end of a chain 29, the rear end being connected to the eye 30 of one of the beams.

Handles 31 are pivotally connected to one of each of the pairs of beams, and is suitably braced by the members 32. These members 32 are connected to the beams by the removable bolts 33, and by taking out these bolts and swinging the handles into vertical positions the said brace members 32 can be again bolted to the beams at points 90 forwardly of the pivotal connections of the handles. Thus the handles are disposed in position to be easily reached by the driver from the seat, which, as clearly shown in the drawing, is disposed slightly to the rear of 95 the handles when said handles are in their vertical position.

By this arrangement the weight of the driver, on the seat, causes the depression of the rear ends of the bars 16 with the result that the forward ends of the bars will exert an upward pull on the chains 29, whereby the beams and cultivator shovels can be more easily handled by the driver.

The attachment is extremely simple in 105 construction and can easily and quickly be applied to or removed from the cultivator. By adjusting the chains the balancing of the weight of the driver and the resistance of the dragging action of the cultivator 110 shovels, can be regulated.

It will be noted that the rear ends of the

bars 16 are turned downwardly to permit them to pass inwardly between the usual beam supporting hooks 14. Each of the handles 31 is provided with a hand grip 31' by means of which said handles are manipulated.

What is claimed is:

The combination with the tongue, the arch, and cultivator beams of a cultivator, 10 of a riding attachment therefor including a pair of notched members disposed longitudinally at the sides of the tongue of the cultivator, the said notches being arranged

to interchangeably receive portions of the arch of the cultivator, a seat carried by the 15 rear ends of the notched members, and chains connected to the forward ends of the notched members and to the cultivator beams.

In testimony whereof, I affix my signature 20 in the presence of two witnesses.

ORVILLE D. BENDURE.
